PROCESS AND APPARATUS FOR TREATING HYDROCARBONS

Filed Sept. 1, 1920

UNITED STATES PATENT OFFICE

LESTER KIRSCHBRAUN, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR TREATING HYDROCARBONS

Application filed September 1, 1920. Serial No. 407,419.

This invention relates to improvements in process and apparatus for treating hydrocarbons and refers more particularly to one adapted to the cracking of petroleum oil to 5 make gasoline or gasoline-like bodies.

The invention also more specifically refers to a so-called continuous process, in which the heating zones and vapor zones are not separate units. In a process of this character 10 the oil to be cracked may be continuously fed through a series of tubes or a coil of pipe seated in the furnace and the hot oil delivered from said tubes by a transfer line to a vapor chamber located preferably outside of 15 the furnace. In processes of this character, it is desirable to maintain the oil in the heating tubes in the liquid phase in order to avoid the precipitation and deposition of carbon in that part of the apparatus which is subjected to the heat of the furnace. In other 20 words, if the oil is raised to such a temperature as to cause vaporization in the heating tubes, the latter will soon become clogged or seriously injured and the operation has to 25 be prematurely terminated.

It has also been found that the difference of a very few degrees of temperature in the oil at the point it leaves the heating tubes is sufficient to cause vaporization and consequent precipitation of carbon. I wish to emphasize that in order to operate the process over an extended period of time, without the necessity of shutting down the plant, it is necessary to maintain the temperature of the 35 liquid at the point of transfer from the heating tubes to the vapor chamber within very narrow limits. If the oil is too hot, this undesirable vaporization takes place in the outlet end of the heating tubes, while if the temperature is not sufficiently high, the proper degree of cracking or conversion is not obtained.

The object of the invention is, first, to insure a constant and uniform temperature of 45 the oil in the heating tubes at the point of the transfer of such oil into the vapor chamber and second, to regulate this automatically by the quantity of the oil being fed into the system.

50 In order to more clearly understand the in-

vention, I have shown the accompanying drawings in which the single figure gives a rather diagrammatical view of an apparatus suitable for carrying out the invention.

Referring to this drawing, I designate the 55 furnace in which is mounted the heating element or coil 2, which may take the form of horizontal extended superimposed tiers or connected pipes or tubes, as, for example, tubes of four inch internal diameter. The 60 oil to be treated is delivered by the pump 3, through inlet line 4 and delivery line 5 to the heating coil. This pump is actuated by motor 6. The oil passes through the heating coil and the temperature is gradually raised to 65 the desired point. The oil, while still in liquid phase, passes out of the coil to the vapor chamber 7 through transfer line 8. The vapors pass out of the vapor chamber 7 through line 9 to condenser coil 10 and thence to receiver 11. This receiver 11 is provided with liquid drawoff line 12, controlled by a throttle valve 13 and gas outlet line 14, controlled by valve 15. The vapor chamber is provided with liquid drawoff line 16, controlled by 75 valve 17.

Describing now more particularly the salient feature of the invention; in the transfer line 8 is interposed a pyrometer 18, which controls the thermostatically operated motor 6. The arrangement is such that when the temperature of the oil in the transfer line becomes too hot, the thermostatic arrangement will increase the speed of the motor and thus increase the supply of fresh cool oil being fed to the heating tubes. Contrarywise, when the oil in the transfer line is too cool, the thermostatically operated motor will automatically reduce its speed and feed less oil to the heating coils. By this mechanism, I 80 am enabled to maintain the temperature of the oil in the transfer line at a predetermined temperature and within very narrow limits. For example, if it is desired to maintain the temperature of the oil at point of transfer to 85 the vapor chamber at 800° F., this arrangement will permit of maintaining the oil within 2° either way. Where a manually controlled valve is relied upon, the temperature in practice will actually vary from 40° to 90 95

50°. This is true for the reason that in order to maintain a close regulation there must be constant variation in the speed of the pump, which is not possible to obtain within narrow limits by manual control. The process will operate whether the oil is cracked at atmospheric pressure or at, say, 100 pounds pressure. By means of this arrangement, the process can be carried out for an extended period of time without producing carbon in the heating tubes.

I claim as my invention:

1. An improvement in an oil cracking process of a continuous type, in which the oil is heated to a cracking temperature while flowing through a heating coil and thereafter delivered to an enlarged zone, which comprises controlling the temperature imparted to the oil in the heating coil by varying the quantity of the oil supplied to the heating coil through thermo-responsive means actuated by variations in the temperature of the oil issuing from the heating coil.

2. An improvement in a continuous oil cracking process, in which the oil is heated to a cracking temperature while flowing once through a heating coil and thereafter delivered to an enlarged reaction zone, which comprises automatically varying the quantity of oil supplied to the heating coil, responsive to variations in the temperature of the oil being transferred from the heating coil to the enlarged reaction zone.

3. In the art of converting heavy into lighter oils, wherein an advancing stream of oil is heated to a cracking temperature and then transferred to a reaction zone, the improvement consisting in controlling the temperature imparted to the oil stream being heated responsive to variations in the thermal condition of the oil stream as it is transferred to the enlarged zone to maintain said stream as it is transferred to the reaction zone at a substantially uniform predetermined temperature.

4. In the art of converting heavy into lighter oils, wherein an advancing stream of oil is heated to a cracking temperature, and then transferred to a reaction zone, the improvement consisting in controlling the heat imparted to the oil undergoing treatment in the heating zone, in regulating such control in response to variations in the thermal condition of the oil stream to maintain said stream as it is being transferred to the reaction zone at a substantially uniform predetermined temperature.

5. In an apparatus for converting heavy into lighter oils, the combination with a furnace, of a heating coil therein, through which a stream of oil is continuously advanced, a reaction zone, means for transferring the heated oil to the reaction zone, means for controlling the temperature imparted to the oil passing through said coil, and thermal means

responsive to variations in the temperature of the oil heated in the coil, regulating said control means to maintain said stream of oil as it is being transferred to the reaction zone at a substantially uniform predetermined temperature.

6. In the art of converting heavy into lighter oils wherein a stream of oil is continuously advanced through a heating coil to be heated to a cracking temperature and then transferred to a reaction zone where conversion occurs, the improvement consisting in controlling the amount of heat applied to the oil stream in transit through the heating zone, in regulating such oil temperature in response to variations in the transfer temperature of the oil by varying the quantity of heat provided relative to the volume of oil advancing through the heating zone during a given period of time to maintain said oil stream as it is continuously transferred to the reaction zone at a substantially predetermined temperature.

7. In an apparatus for converting heavy into lighter oils, the combination with a furnace having a heating zone, of a heating coil disposed therein, means for continuously advancing a stream of oil through said coil, a reaction zone, means for controlling the temperature imparted to the oil passing through said zone by varying the quantity of heat provided relative to the volume of oil passing through said coil in a given period of time, thermal responsive regulating means acting in response to variations in the temperature of the heated oil in the coil for regulating said controlling means to maintain the oil stream as it is being transferred to the reaction zone at a substantially uniform temperature.

8. In the art of converting heavy into lighter oils wherein a stream of oil is continuously advanced through a heating coil to be heated to a cracking temperature and then transferred to a reaction zone where conversion occurs, the improvements consisting in controlling the amount of heat applied to the oil stream in transit through the heating zone, in regulating the temperature to which the oil is raised in response to variations in the transfer temperature of the oil by varying the ratio between the heat provided and the volume of oil advancing through the heating zone during a given period of time to maintain said oil stream as it is continuously transferred to the reaction zone at a substantially predetermined temperature.

9. In an apparatus for converting heavy into lighter oils, the combination with a furnace having a heating zone, of a heating coil disposed therein, means for continuously advancing a stream of oil through said coil, a reaction zone, means for controlling the temperature imparted to the oil passing through

said zone by varying the ratio between the heat provided and the volume of oil passing through said coil in a given period of time, thermal responsive regulating means acting 5 in response to variations in the temperature of the heated oil in the coil for regulating said controlling means to maintain the oil stream as it is being transferred to the reaction zone at a substantially uniform temperature.
